Primary Examiner — Clare E Heflin(74) *Attorney, Agent, or Firm* — Calfee, Halter & Griswold LLP(57) **CLAIM**

I claim the ornamental design for a lighting fixture, as shown and described.

DESCRIPTION

FIG. 1 is a front perspective view of a lighting fixture. The support arms have three-way, one hundred twenty degree overall rotational symmetry, and the outer frame has four-way, ninety degree overall rotational symmetry. The candles, bobeches, and center stem each have a circular horizontal cross-section.

FIG. 2 is a right side elevational view of the lighting fixture of FIG. 1.

FIG. 3 is a top plan view of the lighting fixture of FIG. 1. FIG. 4 is a front perspective view of a second embodiment of the lighting fixture. Each set of support arms has three-way, one hundred twenty degree overall rotational symmetry, and the outer frame has four-way, ninety degree overall rotational symmetry. The candles, bobeches, and center stem each have a circular horizontal cross-section.

FIG. 5 is a front elevational view of the lighting fixture of FIG. 4; and,

FIG. 6 is a top plan view of the lighting fixture of FIG. 4. The broken lines shown on the drawings depict portions of the lighting fixture that form no part of the claimed design.
